UNITED STATES PATENT OFFICE.

ROBERT H. KLINGEL, OF WEST STRATFORD, AND WALTER L. WILKS, OF BRIDGEPORT, ASSIGNEES TO THE HOLMES & EDWARDS SILVER COMPANY, OF WEST STRATFORD, CONNECTICUT.

DESIGN FOR A SPOON, &c.

SPECIFICATION forming part of Design No. 17,777, dated October 11, 1887.

Application filed May 31, 1887. Serial No. 239,881. Term of patent 14 years.

To all whom it may concern:

Be it known that we, ROBERT H. KLINGEL and WALTER L. WILKS, citizens of the United States, residing, respectively, at West Stratford and Bridgeport, in the county of Fairfield and State of Connecticut, have invented and produced a new and original Design for Spoons, Forks, &c.; and we do declare the following to be a full, clear, and exact description of the same, reference being had to the accompanying drawings, forming a part thereof.

Figure 1 is a plan view illustrating the contour of our novel design; Fig. 2, a similar view, a portion of the upper surface of the handle being ornamented; Fig. 3, a similar view showing partial ornamentation and a bead around the upper end of the handle; and Fig. 4 is a similar view, the entire upper surface or face of the handle being ornamented.

The leading features of our design consist in a handle widest near the upper end, the end itself having the form of a flattened curve, the sides then curving inward, diminishing the width of the handle, then curving outward again, forming a rounded swell approximately the width of the upper end of the handle at approximately one-third of the distance from the end of the handle to the base of the spoon or fork, the sides then curving gently inward again down to the shank of the handle.

1 denotes the flattened curve at the upper end of the handle; 2, the diminished inwardly-curved portion below the upper end of the handle; 3, the rounded swell; 4, the curved portion below the swell; and 5 the shank of the handle.

It will of course be understood that while the primary portion of our novel design—that is, the contour—is always the same, the face of the handle may be variously ornamented without departing from the essential principle of the design.

In Fig. 2 we have shown the shank and swell of the handle as covered with surface ornamentation 6 and curved beads 7, surrounding the swell at the sides, extending partially across at the bottom, and extending inward from the sides to the center of the handle in the form of scrolls 8 at the top of the swell.

In Fig. 3 we have illustrated the same general ornamentation as in Fig. 2, but have added a bead, 9, at the edges of the diminished portion 2 and around the flattened

curve at the upper end of the handle, this latter bead extending downward and running into bead 7. It will be seen that in plan the widest portion of the handle is at the upper end thereof, the width at the swell being slightly less than at the upper end of the handle, the width at the curve of the diminished portion 2 being perceptibly less than at the swell, and that below the swell portion 4 curves inward and runs into the shank.

We claim—

1. The design for handles herein shown and described, the same being widest at the upper end of the handle, the extreme end being a flattened curve, the next narrowest portion being a rounded swell between the extreme end and the shank, the next narrowest portion being at the curves between the upper end and the swell, and the next narrowest portion being below the swell, substantially as described.

2. The design for spoon and fork handles herein shown and described, the same consisting of a flattened curve at the upper end, a curved diminished portion below the upper end, a rounded swell below the diminished portion, and an inwardly-curved portion below the swell extending into the shank, the shank and swell being ornamented, substantially as shown and described, and the swell being partially surrounded by curved beads 7, ending in scrolls 8 at the top.

3. The design for spoon and fork handles herein shown and described, the same consisting of a flattened curve at the upper end, a curved diminished portion below the upper end, a rounded swell below the diminished portion, and an inwardly-curved portion below the swell extending into the shank, the shank and swell being ornamented, substantially as shown and described, the swell being partially surrounded by beads 7, and the flattened curve 1 and curved diminished portion 2 being surrounded by a bead, 9, which extends down to and runs into bead 7.

In testimony whereof we affix our signatures in presence of two witnesses.

ROBERT H. KLINGEL.
WALTER L. WILKS.
